UNITED STATES PATENT OFFICE.

J. SEWELL TAPPAN, OF NEW YORK, N. Y., ASSIGNOR TO FISK, CLARK & FLAGG, OF SAME PLACE.

DESIGN FOR A SCARF.

SPECIFICATION forming part of Design No. 17,001, dated November 23, 1886.

Application filed June 26, 1886. Serial No. 206,378. Term of patent 14 years.

To all whom it may concern:

Be it known that I, J. SEWELL TAPPAN, residing in the city, county, and State of New York, have invented and produced a new and original Design for a Scarf for Men's Wear; and I do hereby declare that the following is a full and exact description thereof, reference being had to the accompanying drawing, and to the letters of reference marked thereon, making a part of this specification.

This design for a scarf consists in the novel configuration thereof illustrated in the drawing, and which presents the appearance, as therein delineated, of two extended parallelograms, A and B, of different widths and lengths, bounded laterally by the parallel lines C D C' D', and whose straight lateral lines C and C' on one side and D and D' on the other are connected by intermediate curved lines, E 20 E, completing the design. The longer and

narrower parallelogram, A, is shown as partly broken out in its length. The form of the outer ends, F F, of the parallelograms A and B may be square, as shown in the drawing, or pointed or rounded, without departing from 25 my invention.

I claim as my invention—

The design for a scarf herein shown and described, the same consisting of a scarf whose outer edges comprise two sets of parallel side 30 lines, C D and C' D', at different distances apart, and the intermediate curved lines, E E, connecting them.

In testimony whereof I have signed my name to this specification in the presence of two sub- 35 scribing witnesses.

J. SEWELL TAPPAN.
